ISAAC N. GATES, OF PEORIA, ILLINOIS, ASSIGNOR OF ONE-HALF TO DANIEL R. SHEEN
OF PEORIA, ILLINOIS.

MOLD OR FORM FOR CONCRETE WALLS.

963,431.

Specification of Letters Patent.

Patented July 5, 1910.

Application filed July 27, 1908. Serial No. 445,642.

To all whom it may concern:

Be it known that I, ISAAC N. GATES, a citizen of the United States, residing at Peoria, in the county of Peoria and State of Illinois, have invented certain new and useful Improvements in Molds or Forms for Concrete Walls; and I do hereby declare that the following is a full, clear, and exact description of the invention, which will enable others skilled in the art to which it appertains to make and use the same.

This invention relates to a mold for constructing hollow or partially hollow concrete building-walls.

15 The invention also relates to the construction of walls having air cavities or passages, and it relates further to a mold or form provided with removable cores for making building walls with air cavities and 20 said walls being constructed in a single mass of concrete on the site it is occupy.

One of the objects of the invention is to construct a building-wall of any given size in one unbroken member or unit having air 25 passages extending therethrough preferably from top to bottom such wall being formed of a composition of sand, gravel, crushed stone or other like substance combined with cement, coal-tar or other adhesive substance 30 usually employed for forming artificial stone or concrete.

A further object is to provide a form of mold by which a wall, such as described may be constructed quickly and easily and at the 35 least possible expense for the paraphernalia employed.

A further object is to provide a mold of peculiar construction by which a wall such as described may be constructed easily and 40 quickly by an unskilled person.

Another object is to provide a mold and cores for the same for use in constructing a wall with air passages and provide for said cores a suitable covering to prevent contact of the concrete therewith and from 45 which covering said cores can be easily removed when desired.

Various other objects will appear in the following specification, and the invention 50 besides the objects above enumerated relates to certain details of construction as will be pointed out herein and form the subject of certain of the claims.

In the appended drawing, Figure 1 is a transverse section of my mold into parts of 55 which the cement or concrete has been placed. Fig. 2 is a side elevation of part of the mold shown in Fig. 1 with parts broken away to show the interior. Fig. 3 is a plan of the mold and a series of cores 60 suspended therein. Fig. 4 is a perspective view of a portion of the mold showing a core suspended therein and a protecting housing or cap therefor. Fig. 5 is a plan of the mold showing a different arrangement of the cores from that shown in Fig. 6. Fig. 6 is a perspective view of one of the coverings for the cores. Fig. 7 is a perspective of a covering for certain bolts which are employed to hold certain portions of the 70 mold together. Fig. 8 is a side elevation of a bar for supporting a core, and employed also as a gage for the mold-sections and to secure the sections of the mold relatively. Fig. 9 is a plan of a portion of a concrete 75 wall as I prefer to construct it. Fig. 10 is a sectional elevation of a portion of a building showing the manner of using its spaces for ventilating and heating purposes.

Before entering upon the description of 80 my mold and its product, I desire to state some of the advantages to be derived therefrom.

It is my purpose in constructing a wall to leave air spaces or passages which preferably extend vertically from bottom to top of the wall. In order that these passages may be left while building the wall I employ a core of short length, which as the wall rises higher and higher can be raised 90 from time to time and built around with cement as section after section of mold sections are added, so that in constructing a wall of this kind it is not necessary to have a great many parts or accessories, in the 95 matter of cores at least, and in order that this method may be readily and easily carried out I have provided a suitable covering for the cores such for instance as paper or other suitable material for preventing 100 the cement adhering thereto. If the cores are not in contact with the cement they can be easily raised out of the wall under construction and used for further continuing the height of the passage or cavity left by 105 it. This provision besides permitting the

cores to be very easily removed prevents damage in any way to the structure in the withdrawal thereof.

In the drawing and specification letters 5 of reference correspond.

- A A represent two sides or sections of a mold which, in Figs. 1 and 2 are the lower portions of such mold while in these figures, also, B B indicate two other mold-sections 10 mounted upon the top edges of those just described. These mold-sections are preferably made as large as possible without being too bulky to be conveniently handled and in using them a low foundation of cement 15 or other desired material indicated at C may be constructed of the same thickness the finished wall is to be, the lower edges of the mold being placed each side thereof, as indicated in the first four figures, and held 20 in that position by any desired means such, for instance, as bolts D which pass therethrough and receive suitable tightening devices E preferably made so as to be easily grasped by the hand. The same means may 25 be employed at the top of the mold-sections as shown in Figs. 1, 2 and 4 or in place thereof or in addition thereto I may employ a gage F also shown in Figs. 1, 2, 4 and 8 consisting of a member having a notch G in 30 its lower edge near each end into which enter the top edges of the sections A, said notches G firmly holding the said sections a fixed distance apart. Located within the mold at such places as air spaces are desired, is a series of cores H their positions being shown in dotted lines in Fig. 2, the resulting spaces or passages being shown in the finished wall in Fig. 9. In Figs. 1 and 2 the cores are shown suspended from the 35 member F already described, while in Fig. 4 the cores rest upon the foundation C being supported at its upper end by said member F. The cores are provided at their tops with vertical slits J, one of which is shown 40 in Fig. 8, to receive the member F. The upper ends of the cores are reduced in size for convenience, and a pin K extends therethrough and through the members F. By 45 this means the cores are held in a vertical position and are prevented from movement at their lower ends by causing the member F and the bottom of the slit to be brought into firm contact. Or in addition to this or 50 in lieu of it I may place blocks L between the cores and the sides A A as shown which 55 will serve to prevent the lower ends of the cores moving. But in Fig. 3 I have represented stones or other easily procured substance at M to answer the same purpose. 60 Covering the top of each core is an A-shaped cap N which is slotted at each side as indicated at O so as to fit over the said supporting member or gage F as clearly shown in Fig. 4, this being employed to protect 65 the parts when filling in the concrete. Said

cap is turned inward toward the core and serves to protect and hold a covering P applied to the core. This said covering may consist of paper, or asbestos, or other suitable material. If of paper the covering is oiled or otherwise treated to make it impervious to water in which case one or two thicknesses will be sufficient to keep the cores dry but if untreated paper is used two or more thicknesses are preferable. The material is wrapped upon the cores before the latter are placed in position or it may be furnished in a hollow form and slipped thereon. 75

In Fig. 7 I show a tube Q of paper, asbestos or other suitable material for covering the bolts D hereinbefore described, the holes in the sides A of the mold, for receiving the bolts being made sufficiently large to receive both the bolts and their coverings. 80

In assembling the mold the sides A are placed in position as before described and the bolts with their paper tubes are then pushed through the sides and secured in position by the means already described. In the figures I illustrate by the letter R 90 two flaring boards which rest upon the top edges of the mold and which are held relatively rigid by any suitable means for instance by using braces S extending across their tops. Secured to their outer surfaces 95 and extending below their edges are suitable straps T which engage the outer surfaces of the said sides A and serve to hold said boards in position and the latter are provided with notches R' in their lower 100 edges to receive the member F so that said boards can be set down in place, said notches R' also regulating the distance between the members F. All the parts being in place and in readiness for work, the concrete is 105 filled into the molds along its entire length or from corner to corner of the building, or as far as the molds may extend, the caps N during the filling operation fully protecting the cores and their paper coverings. 110 After the mold has been filled the flaring sides R are removed and the cores are withdrawn from their positions and out of their coverings P a 1, if desired, may be slightly tapered to facilitate their removal. Having 115 removed the cores after the cement has sufficiently set, additional mold sections B already described are mounted upon the top edges of the sections A and held in position at their upper edges by employing the members F or by means of the bolts D, or both, as already described. Preferably the top edges of the lower sections A are rabbeted as are also the lower edges of the section B so that one may rest in the other and form 120 a flush interior surface for the mold. Secured to the top edges of the said section A, at intervals, are cleats U whose upper ends serve to hold the sections A and B relatively 125 rigid. But other holding devices or equiva- 130

lents of the cleats U may be readily employed as will be suggested to the mind of the skilled mechanic. The member F having been placed in position as described the 5 cores are once more provided with new coverings P, and suspended from the member F with their lower end hanging within the cavities formed at the first operation, the caps are once more placed in position and 10 the flaring sides R, constituting the hopper, are put in place. The concrete is once more filled in to the desired height and another section of the molds placed in position and so on until the wall of the desired height 15 is obtained. After the concrete is fully set so as to bear its own weight the mold sections are removed after withdrawing the bolts D leaving the paper tubes Q in position the latter being merely used to allow 20 said bolts to be easily removed. The holes left by the bolts may be closed with cement so that the finished wall will present a tidy appearance.

In Fig. 5 I show a plan of a mold wherein 25 in a large number of cores are arranged in such a way as to provide a considerable number of air spaces which are arranged in a zigzag or "staggered" manner, and all have the means already described, for supporting them. Mounted upon some of the cores I show a metal cap V corresponding, in respect to utility, to the caps N of the other figures. This figure illustrates certain 30 of the bolts D or rather their heads and clamping member E as described for the other figures. Since the cores in this form 35 of mold do not admit of the said bolts passing between them, some of the single cores or those shown by themselves are provided 40 at their lower ends with notches (not shown) to allow them to be readily put in place or removed without interference from said bolts. I also show the manner of building the angle of two walls extending at right 45 angles to one another. The mold members of one wall abut against those of the other and certain of them carry corner brackets W which serve to position the end of the other sections in place. Fig. 2 also carries 50 out this idea the corner brackets being indicated at X there being one also above it indicated at Y which has a flaring upper portion for supporting the upper member R of the hopper but this will be clear without 55 description.

Figs. 1 and 2 show a floor beam or joist 60 which may be set in position during the building of the wall. For instance I-beams 2 extend through holes 3 of the sides B of the mold and rest upon the section A beneath and the concrete is filled in around it as the building of the wall proceeds. The 65 said holes 3 are, in reality, mere notches cut in the lower edges of the section B so that the latter can be set down over said beams.

Fig. 9 shows the manner in which I preferably construct the corner at the joining of two walls. The passages do not extend into the corner but those of one wall terminate substantially flush with the inner line of those of the other wall so as to leave a solid corner extending the full height of the building 70 for strengthening purposes.

Fig. 10 illustrates one way in which the air passages may be utilized for ventilating 75 and for heating purposes, for instance, I have indicated three rooms, one above another, the lower one being for instance a basement room for a furnace. If desired to ventilate each one of these rooms provision 80 is made by the insertion of a block (not shown) in the wall in each room opposite a passage it is desired to open said blocks lying between the core and the side of the mold so that after the wall is completed and 85 the block is removed the opening will be left.

In bringing out my invention I am fully aware that it is not new to provide air spaces 90 in walls when constructed of hollow cement blocks or tiling one built upon another to form a wall but I believe it is new to construct a continuous wall or monolith after the manner described herein upon the site the building is to occupy and to provide for 95 forming the air passages therein. Considerable advantage arises in building a solid wall of cement over that of blocks since a stronger structure will be the result. Experience has shown that in making blocks by 100 any of the approved methods it is impracticable to use a very wet cement whereas in my method of construction there is nothing to prevent the use of a well puddled mixture. By being thoroughly wet the particles 105 of cement are changed in condition and form a very much more homogeneous mass. In addition to the statement above made as to my knowledge of the existing art I may state also that I am also aware that solid 110 concrete walls have been constructed on the site they are to occupy but so far as I know they were made without the ventilating passages.

By my method in constructing building- 115 walls I am enabled to work with comparatively few of the cores H since after having constructed a portion of the wall in which, for instance fifteen or twenty of such cores have been used these may be withdrawn and 120 carried to another portion of the wall and thence to another portion and so on around the entire building. The cores may be hollow so as to be light in weight and they may be made of wood or metal or even of tile, 125 and the sections A and B may also be made of wood or metal. Besides employing coverings for the cores, coverings may be likewise employed to protect the inner surface of the mold sections where said sections 130

would come in contact with the cement, such a provision being made in order to permit of making a perfectly smooth finished surface for the structure.

- 5 Considerable advantage arises from the manner in which the cap or hood N which covers the core II is used. It is not secured to any of the other parts of the device. In addition, the cores are separate from the members F and can be placed in position or removed at will and as this is possible various combinations can be made, as for instance, without special structures more than one core can be affixed to a member F as 10 in Fig. 5 to arrange for the plurality of staggered air spaces described by the use of the removable pins K. A hood or cap can now be placed upon each core to protect it, and the two edges thereof in being inturned 15 toward the core engage the covering and hold it from slipping down and at the same time prevent the cement from lodging thereon or getting between it and the core said cap being held securely in its adjustment by being slotted to receive and to ride 20 astride the member F which prevents movement in one direction and by engaging the core as described it is prevented from moving in the other direction.
- 25 30 In the use of my device no special structure is necessary to arrange for building a wall of any desired form, for since all of the parts are separable they may all be assembled as wanted so as to admit of building the 35 form of wall structure desired. Another advantage is, that as the cap is in no way affixed to the hopper the cores can be placed any distance apart along the top edge of the sides A and the caps adjusted to them as al- 40 ready described.

Having described my invention, I claim:—

1. A mold for making a hollow concrete structure consisting of means forming an enclosure for said structure, a member lying 45 across and upon said means and bridging the recess inclosed by it, a core for attachment to and to be suspended from the member, a removably inserted device extending transversely through the member and the 50 bifurcated portion of the core whereby to suspend said core from said member, a cap to cover the core and the member, and a covering for said core and from which it is

withdrawn after the structure is formed, said cap adapted to engage and hold said covering during the forming of the structure. 55

2. A mold for constructing building walls consisting of the side portions of said mold, a member extending across and resting upon them, a core suspended from said member, a covering for the side of said core, a protecting cap to engage the member and to cover the end of the core and the end of said covering and adapted to engage and hold the 60 said covering and removable from said core and from the member. 65

3. A mold for constructing building walls consisting of the side portions of said mold, a member extending across and resting upon them and provided with notches to receive the said portions, a core suspended from the member and detachable therefrom, a covering for the core, means to secure said core to the member, a cap to cover and protect said member, the core, and the covering of said core and adapted to hold said covering, and removable from all of them. 70 75

4. A mold for constructing building walls consisting of the side portion of said mold, a member extending across and resting upon them, a core suspended from the member between the said portions, a covering for the core from which it is removable, a cap to cover the top of the core and that portion of the member above it, and removable from both and having inwardly extending lower edges adapted to engage the said covering. 80 85

5. A mold for constructing building walls consisting of the side portions of said mold, a member extending across and resting upon them, a core suspended from the member between the said portions, a covering for the core from which it is removable, a cap to cover the top of the core and that portion of the member above it, and removable from both and having inwardly extending lower edges adapted to engage the said covering, 90 said cap having a notch in two of its opposite sides to receive the member. 95 100

In testimony whereof I affix my signature, in presence of two witnesses.

ISAAC N. GATES.
